CLAIM

The ornamental design for a shoe outsole, as shown and described.

DESCRIPTION

FIG. 1 is a front perspective view of a shoe outsole showing our new design;

FIG. 2 is a bottom view thereof;

FIG. 3 is a rear perspective view thereof;

FIG. 4 is an enlarged view of FIG. 1 with environmental portions removed for clarity;

FIG. 5 is an enlarged view of FIG. 2 with environmental portions removed for clarity; and,

FIG. 6 is an enlarged view of FIG. 3 with environmental portions removed for clarity.

The broken line immediately adjacent to the photographic area defines the bounds of the claimed design and forms no part thereof. The broken lines showing the remainder of the shoe represent unclaimed subject matter and form no part of the claimed design.
